1 Claim. (Cl. 18—8)

This invention relates to continuous spinning of rayon and more particularly to methods of and a machine for the production of high quality rayon yarn such as viscose heavy denier yarn for reinforcing rubber articles such as cord tires and the like, on a commercial scale.

In tube spinning equipment each yarn to be aftertreated is spun in an acid bath, subjected to hot water stretching, if desired, and then propelled successively through a group of glass tubes by treating liquids so that the yarn emerging from the last tube of a series is ready for drying. This type of aftertreatment involves many inherent advantages over both the discontinuous and the older continuous spinning systems, but, to exploit those advantages to the fullest possible extent, it was necessary to design machines of large productive capacity.

In the development of commercial machines for tube spinning, the cost, safety and efficiency aspect of plant space, labor, accessibility for spinning-in, localized repair without cessation of spinning, maintenance of ambient atmosphere and circulation of treating liquids for the service of a large number of spinning positions are all factors that need to be considered in mutually dependent relationship.

It is, therefore, an object of this invention to provide a tube spinning machine of high productive capacity which is characterized by the compact arrangement of the tube groups associated with each spinning position as well as easy accessibility of tube groups and individual components thereof without necessity for general shutdown for localized repair.

It is contemplated according to the present invention to provide liquid supply and gas withdrawal connections which are easily and conveniently shifted from operative to inoperative positions to afford access to the aftertreating equipment with which they are associated.

Other objects and advantages of this invention will be apparent upon consideration of the following detailed description in conjunction with the annexed drawings wherein:

Figure 1 is a top plan view of a two-sided rayon spinning machine constructed in accordance with the principle of the present invention, the gas hoods being removed for convenience of illustration;

Figure 2 is a perspective view of one side of the machine of Figure 1;

Fig. 3 is a view in plan of a portion of the side of the machine shown in Figure 2;

Figure 4 is a view in section taken on the line 4—4 of Figure 3;

Figure 5 is a view in cross section to an enlarged scale of the spinning side of the machine;

Figure 6 is a view in cross section to an enlarged scale of the finishing side of the machine;

Figure 9 is a detailed view in vertical section of a typical jet box with which the machine is provided;

Figure 10 is a view in longitudinal section of the lower end of the finishing side of the machine of Figure 2;

Figure 11 is a fragmentary view in elevation of one of the spinning points of the machine;

Figure 12 is a fragmentary view in elevation showing a typical vapor hood with which the machine is provided;

Figure 13 is a detailed view in transverse section of the lock and articulation arrangement for a vapor hood;

Figure 14 is a view in vertical section of the lock and articulation arrangement for a vapor hood;

Figure 15 is a liquid flow distribution layout for the various treating liquids used in treating rayon in the machine of the present invention; and

Figure 16 is a view in side elevation of warp drying apparatus.

A two-sided commercial machine, constructed in accordance with the principles of the present invention, is very large indeed since each side may include a large number of spinning positions and each spinning position usually includes a spinneret, two godets and a group of aftertreating tubes. Naturally, the number of aftertreating tubes is variable depending upon the treatment to be accomplished, as is the number of godets dependent upon the stretch conditions sought to be brought about. A typical machine is illustrated in Figure 1 and that machine has one hundred and forty-four spinning positions, each position having associated with it eight aftertreating tubes.

In the machine of Figure 1 seventy-two spinnerets at one side of the machine are served by a very long common spinning bath tank 10, while seventy-two spinnerets on the other side of the machine are served by a similar elongated common spinning bath tank 11. Adjacent bath tanks 10 and 11 are hot water bath tanks 12 and 13, respectively. All of the tanks 10, 11, 12 and 13, are disposed in mutually parallel relationship.

The yarns, after leaving the hot water baths 12 and 13, are led to and through a group of aftertreating tubes

14. In Figure 1 the total of the groups 14 of aftertreating tubes which are associated with the baths 10 and 12, is designated by the numeral 15, while the total of the tube groups 16 for aftertreating the yarns spun in the bath 11 is designated by the numeral 17. The various

tube groups 14 or 16 are disposed with their general axes at right angles to the long axis of the bath tanks 10, 11, 12 and 13. The tube groups 14 serve to establish a plurality of yarn paths between the hot water bath 12 and a V-section trough 18, which slopes downwardly from left to right as viewed in Figure 1 and receives the yarns issuing from the various tube groups 14. A similar V-section trough 19 slopes in the same direction as the trough 18 and it serves the series 17 of tube groups 16, which are associated with bath tanks 11 and 13 at the other side of the machine.

The advantage inherent in the relative locations of major parts of the machine, as shown in Figure 1, can be better appreciated after the structure and function of one of the one hundred and forty-four spinning positions 60 is described and analyzed. Hence this description will cover first a single spinning position and then relate that position to the assembly constituting one side of the machine. Except in Figure 1, both sides of the machine are not illustrated since the two seventy-two position sides are mirror image mutual equivalents and the advantages of their positioning relative to one another is fully apparent from the single figure in which both are illustrated.

The exact manner in which a spinneret, the godets and 70 the associated group of aftertreating tubes coat can best be understood by concurrent reference to Figures 4 to 9, inclusive, and Figure 11. While Figures 7 and 8

are concerned with the tubes serving but a single spinneret, it will be understood that the subassembly associated with each spinneret is the same throughout both sides of the machine for the entire one hundred and forty-four units except for differences in the length of the connections between the tube groups and the troughs 18 and 19.

In Figures 5 and 11 there is shown at 20 one of the spinnerets which is located in the spinning bath tank 10. Yarn issuing from this spinneret is drawn off by godet 21 from which it is led downwardly over a guide roller 22 located in hot water bath 12 and then upwardly to godet 23. The spinning solution is delivered to the spinneret 20 through conventional means. Godet 23 is operated at a higher peripheral speed than godet 21 and serves to stretch the yarn about 75% in its passage through the hot water bath in the tank 12. After leaving the godet 23 (see Figure 11) the yarn is passed downwardly in a path tangential to the peripheral wall of the godet and is automatically washed by a jet of water issuing from a nozzle 24 into a deflector 25 which guides the running end of yarn to a low pressure zone 26 (see Figure 5) created by a jet of liquid coaxially directed by a nozzle 27 into the flared mouth of a tube 28. Once the yarn is drawn into the tube 28, it is there propelled by the liquid issuing from the nozzle 27 until the tube 28 discharges into a jet box 29. Referring now to Figures 7 and 8, the yarn entering the box 29 from the tube 28 first passes along deflector 30 and then in succession through tube 31, deflector 32, tube 33, deflector 34, tube 35, deflector 36, tube 37, deflector 38, tube 39, deflector 40, tube 41, deflector 42, and finally tube 43. As can be seen in Figure 8, the deflectors 32, 36, and 40 are mounted in a jet box 44 which is similar to, but positioned to face, the box 29, whereby the tubes may extend back and forth to reduce the overall length requirements of a tube group 14.

From tube 43, which is the eighth tube of the group just described, the yarn is led over the end of the jet box 44 and is led into a large tubular conduit 45 from which it falls into V-section trough 18 to be washed downwardly to form a part of a warp which is eventually led to drawoff rollers 46 at the downstream end of the V-section trough 18, see Figures 2 and 10.

The washing-in device which causes the yarn to enter the low pressure zone at 26 from the godet 23 forms per se no part of the present invention but is shown in U.S. Patent No. 2,675,690, dated April 20, 1954.

The jet boxes 29 and 44 correspond to those shown in U.S. Patent No. 2,724,956, dated November 29, 1955, and per se form no part of the present invention.

The basic idea of the introduction of running yarns into, and their propulsion through, aftertreating tubes by aftertreating liquids is explained in U.S. Patent No. 2,725,276, dated November 29, 1955.

The construction of the trough 18 and the formation of warp therein is shown in U.S. Patent No. 2,789,339, dated April 23, 1957.

While the applications cross-referenced above will afford information regarding the structure and function of some of the components of the present invention, it is proposed to describe those components quite fully herein so that their mutual association and association with other elements of the machine can be appreciated.

While the yarn issuing from the tube 43 passes through a tube 45 of large cross section which leads to the near edge of the trough 18, it is apparent from Figure 8 and from Figure 6 that the trough 18 is much deeper and much wider at the downstream end than it is at the upstream end. Consequently, while there is an equivalent to the tube 45 for each group of aftertreating tubes, the tubes which carry the yarn from the last aftertreating tube to the trough 18 vary in length from a maximum tube 45' of Figure 6 to a minimum tube 45" of Figure 6 so that the yarns issuing from the large diameter carry-

over tube will be laterally offset to run longitudinally of the trough 18 as a warp.

It is apparent that the speed of propulsion of yarn through tubes depends upon the velocity of the treating liquid and the length and cross section of the tubes. In order to standardize on liquid pressures which will maintain uniform yarn velocity in the tubes, all of the tubes are made of the same length and internal cross section. It can be seen that this delicate balance would be upset if each of the tubes 43 were made a different length so that, regardless of position, all of them would reach the edge of the trough 18. To solve this problem all tubes 43 are made alike and the tubes 45 are made of such great internal diameter as to have no effect upon the pressure-velocity characteristics of the liquid issuing from tubes 43. Thus, in their effect upon flow, the tubes 45 may be regarded as open troughs.

Inasmuch as the spinning-in and aftertreating operations in the tube assembly are more or less automatic, 20 and manual handling of the yarn during regeneration is not required, treating liquids having high temperatures may be employed. For example, treating liquids having a temperature above 90° C. have been employed in the above-described tube treating process. The use of these 25 excessively hot treating solutions is one factor contributing to a reduction in the total time required for completely regenerating the viscose rayon yarn. The yarn passes through the entire aftertreating system in a remarkably short time. For example, at a spinning speed of about 76 meters per minute, it has been found that the yarn passes through eight treating tubes each 32 inches long in around seven seconds. In view of the fact that not more than seven or eight seconds are required for the 30 yarn to pass from the initial spinning bath 10 through the stretching operation and into the first treating tube 28, the total time required for transforming viscose solution into substantially completely regenerated and finished viscose rayon yarn is less than twenty seconds. Considering the many physical and chemical changes which occur 35 during this transformation, the shortened treating time is indeed phenomenal.

It is important to note that the abbreviated treating time mentioned above is not achieved by the use of high temperatures alone. An even more important factor is the tension condition of the yarn during the aftertreatment. Since the yarn is conveyed through the treating tubes solely by the passage of the liquid flowing through the tubes, it is subjected to a negligible tension during the time it is being aftertreated. The tension on the yarn 45 is only about 10 grams as it enters tube 28 and it is reasonable to assume that this tension does not increase appreciably as the yarn proceeds through the other tubes. By observation it is apparent that the yarn in the tubes is in a substantially relaxed condition; the filaments are 50 fully separated and dispersed with the liquid freely penetrating between them. This relaxed condition of the 55 yarn is of primary importance in the practicing of the present invention.

In a typical aftertreating arrangement, tube 28 is supplied with water containing 0.16% H_2SO_4 at 90° C., tube 31 is supplied with 4% sulphuric acid at 90° C., tube 33 with 0.1% H_2SO_4 and tube 35 with water at 90° C., tube 37 with 0.1% sodium bicarbonate at 90° C., tubes 39 and 41 with water at room temperature and tube 43 with a finishing solution at room temperature. Even without a specific desulphurization treating liquid, the sulphur content of the treated yarn is abnormally low, usually averaging less than 0.05%.

Heretofore, the bare description of the movement of the yarn through a group of tubes from the spinneret to the warp-forming trough has not been concerned with the manner in which the treating and propelling liquids are delivered for use. In a commercial machine, however, supply of large numbers of different treating liquids and the location of parts for convenience of adjustment

for repair is of great importance. To this end the frame of the machine of the present invention is so constructed as to afford convenient support for fluid conduits as well as easy operator access thereto which result in operating efficiencies of considerable magnitude. Turning now to Figures 4 and 5, the frame includes main standards 48, 49 and 50, suitably braced for rigidity. The standards 48 and 49 are interconnected by girders 51 and 52 while a girder 53 defines with standard 50 a right angle construction which is braced by an element 54. Between the standards 49 and 50 there is an arch-like structure defined by sloping standards 55 and 56 connected at their top by a short girder 57.

The girder 52 serves to support spinning bath tank 10, hot water bath tank 12 and the entire associated assembly on the spinning side of the machine, including two rows of godets and a catwalk 58 useable by personnel working on the spinning side of the machine. Cross members 59 are supported from the framework by adjusting screws 60 so that the level of the tanks 10 and 12 may be adjusted. The frame elements shown in the cross-sectional views constituting Figures 4, 5 and 6 occur repeatedly at intervals along the machine. Conveniently these intervals may be six spinning positions apart. The frame elements are, of course, interconnected longitudinally by suitable girders or structural elements, now shown.

The structure comprised of standards 50, girders 53 and braces 54, longitudinally interconnected, supports the V-trough 18 and a catwalk 61 serving the textile or finishing side of the machine. The groups of aftertreating tubes are supported above the arch girder 57 and a catwalk 62 overlies the groups of tubes so that operators may concurrently work different stations on the machine from catwalks 58, 61 and 62. In view of the position of girder 57, the floor of the plant provides another walk at 63 underneath the walk 62 and convenient to the various conduits which supply liquids to the tubes with which the machine is equipped.

In order to serve the tube groups 14 shown in Figure 1, the aftertreating liquids are circulated in manifolds, distributed to the appropriate jet boxes, used in the tubes, recovered in the appropriate jet box and returned to a manifold. To explain the principles of treating liquid circulation, a typical series of aftertreatments will be described.

The first aftertreating liquid to be supplied to a freshly spun yarn is delivered to manifold 64 shown in Figure 8 and from that manifold is delivered to the seventy-two pipes 65 each leading to a nozzle 27. This liquid treats the incoming yarn in the tubes 28 and is recovered in the box 29. To this end, the jet boxes, such as boxes 29 and 44, are provided with liquid recovery compartments under each of the deflectors.

The deflectors 30, 34, 38 and 42 are mounted on a bar 66 for lateral shifting to and from a position registering with the ends of the tubes 28, 33, 37 and 41, respectively, see Figure 9. Deflectors 32, 36 and 40 are mounted on a bar 67 similar in structure and function to the bar 66. Underneath deflectors 30, 34, 38 and 42 and in registry with the ends of the tubes lie liquid recovery compartments 68, 69, 70 and 71, respectively, and similar compartmentation exists in the box 44 where compartments 72, 73 and 74 underlie deflectors 32, 36 and 40, respectively, as shown in Figure 7. When spinning-in is complete, each aftertreating tube, except tube 43, discharges into a compartment and each compartment has a drain by which the liquid recovered therein can be recycled.

With the foregoing background, the circulation of liquid for the entire machine can be understood, the feeds and returns to all of the tube groups being like those shown and described in conjunction with boxes 29 and 44.

During spinning-in, the yarn issuing from tube 28 is guided by deflector 30 to the mouth of tube 31. Liquid

is supplied to the tube 31 from manifold 75 through conduit 76 terminating in a nozzle like nozzle 27. Yarn issuing from tube 31 discharges into deflector 32 and is guided thereby to the mouth of tube 33. Tube 33 is supplied with liquid from a tube 77 which is connected to manifold 78. The yarn continues similarly from tube 33 to deflector 34 to tube 35 to deflector 36 to tube 37 to deflector 38 to tube 39 to deflector 40 to tube 41 to deflector 42 to tube 43 and finally to oversize tube 45 leading to trough 18.

Tubes 35, 39 and 43 are supplied from conduits 79, 80 and 81, respectively, issuing from supply manifolds 82, 83 and 84. Tubes 37 and 41 are supplied from conduits 85 and 86, respectively, issuing from supply manifolds 87 and 88.

During spinning-in while the deflectors are in the position shown in Figure 7, the liquid and thread from each tube are guided by the deflector to the mouth of the next tube of the group. Accordingly, liquid recovery is not effected during spinning-in and small liquid entrainment occurs. The liquid which is not entrained is discharged to waste through waste outlets 89 and 90 with which all of the boxes such as 29 and 44 are equipped. These waste outlets in the boxes 29 lie on the opposite side of a transverse partition 91 from the compartments 68, 69, 70 and 71. A similar partition 92 transversely subdivides each box 44. The result of these partitions is to subdivide each box into a number of small compartments one under the end of each tube and a single large compartment for waste recovery. The large waste recovery compartment of box 29 bears reference numeral 93 and the equivalent waste recovery compartment for box 44 bears reference numeral 94.

Waste from the various compartments such as 93 and 94 is connected by flexible tubular drains such as 89 and 90 to waste manifolds 95 and 96. Waste manifolds 95 and 96 are drained by pipes 97 and 98 connected at the low point of the respective manifolds.

Thus provision for waste during spinning-in is made and partitions 91 and 92 are made low enough so that the clogging of the drain for any of the compartments 68 to 74, inclusive, results in spillage from the clogged compartment into one of the compartments 93 or 94. During all but a few seconds, while spinning-in is being effected, the described system provides for full liquid recovery without intermixing.

Once spinning-in is completed and the yarn is running in a complete tube group such as that shown in Figures 7, 8 and 9, the deflector rods such as 66 and 67 are shifted axially to move the deflectors out of registry with the respective tube ends. When this happens, the yarn continues to run to the mouth of the next tube of the system but the liquid from each tube discharges into the appropriate one of the compartments 68 to 74, inclusive. So that the treating liquid may be recovered, each of the compartments 68 to 74, inclusive, is connected to a liquid return manifold. In Figure 5 it can be seen that compartment 68 is connected by a flexible tube 99 to manifold 100. Compartments 69, 71 and 72 are similarly connected by flexible tubes 101, 102 and 103 to manifolds 104, 105 and 106, respectively. The compartments 72, 73 and 74 from box 44 are connected by flexible tubes 107, 108 and 109 to manifolds 110, 111 and 112, respectively, as shown in Figure 6.

Upon reference to Figure 15 a typical liquid circulation system for aftertreating tire yarn can be seen. In that figure the supply and exhaust manifolds are represented as blocks and all of the seventy-two tubes through which the liquids pass from one manifold to the other are represented by a single solid line numbered to correspond to the appropriate treating tube of Figure 7.

Beginning then with the tubes 28, it is seen that they are supplied with hot water from a tank S-1 and that manifold 99 drains to sewer. Water is supplied to tank S-1 through a temperature control heater 113 by a pump 114

which draws from a recovery tank R-1 which receives from manifold 104 the discharge from tubes 33. Tubes 33 are supplied from manifold 78 which is fed from tank S-3. Tank S-3 is supplied by a pump 115 which delivers water from recovery tank R-3 through a temperature control heater 116. The water in tank R-3 is recovered from manifold 111 fed by tubes 35. Tubes 35 are supplied from a tank S-4 through manifold 82. The tank S-4 receives its water through a heater element 117 from a pump 118 drawing from a tank R-4. Tank R-4 is supplied from manifold 112 which is fed by tubes 39 which in turn are supplied from manifold 83. Manifold 83 is supplied from tank S-6 which is fed from tank R-6 by a pump 119 delivering through a heater element 120. Tubes 41 are supplied with fresh soft water heated to the proper temperature. This water is discharged from tank S-7 through manifold 88. The recovery from tubes 41 is received in manifold 106 and delivered to recovery tank R-6.

It can now be seen that for treating tire yarn the first, third, fourth, sixth and seventh tubes of each group may contain water or water containing small amounts of acid. The water which first contacts the newly spun yarn has already contacted yarn on four previous occasions and it is not until the fifth water treatment that the yarn encounters fresh water.

In the second tube of each group, the tubes 31, the yarn is treated with sulfuric acid supplied to tank R-2 and delivered from it by pump 121 through heat control element 122 to supply tank S-2. The tank S-2 feeds manifold 75 and the recovery manifold 110 feeds back to tank R-2. Make up liquid is supplied to tank R-2 as indicated in Figure 15.

The fifth tubes of each group, tubes 37, are supplied with NaHCO_3 by a system identical to acid supply system for tubes 31. Sodium bicarbonate recovered from manifold 105 is discharged into tank R-5 from which pump 123 delivers it through a heat control element 124 to tank S-5. From supply tank S-5 the sodium bicarbonate is delivered to manifold 87.

The only other solution is finishing solution which is delivered from the tank S-8 to the tubes 43 from the manifold 84. This solution is not recovered in a manifold at all but passes from the tubes 43 through the large tubes 45 into the trough 18. The finishing solution stays with the yarns as they move along the trough during spinning-in and it moves parallel to the warp of yarns running above the trough 18 during the remainder of the doff. At the end of the trough 18, the finishing solution is discharged through a chute 125 to a screened tank marked 126 in Figure 10 and marked R-8 in Figure 15. From the recovery tank, to which make up may be added through line 127, a pump 128 delivers the solution to tank S-8. If further finish is supplied to the yarns while they are running as a warp beyond the lower end of the trough 18, the slasher pan may be supplied in parallel with the tubes 43 as can be seen in Figure 15.

In Figure 15 all of the supply tanks are shown as above the recovery tanks. This is actually true in the machine where the supply tanks are disposed higher than the tube groups to give a uniform head or pressure at the supply manifolds which, in turn, results in uniform flow through the tubes. By arranging the heaters between the recovery tanks and the supply tanks, the likelihood of entraining air is reduced.

If reference is again made to Figures 5 and 6, it will be noted that all of the drain connections from the boxes 29 and 44 include a flexible portion, see parts 89, 90, 99, 101, 102, 103, 107, 108, and 109. A flexible sleeve is also included in all of the liquid supply lines to the boxes 29 and 44, typical sleeves being shown at 129 in the line 76, and 130 in the line 77. These sleeves are located near the respective boxes. Similar sleeves also connect the part of treating tube that runs between the jet boxes

to the part thereof that lies within the boxes. See typical sleeves 131 and 132 in Figure 8.

By the use of these flexible elements it is easy to isolate any one set of boxes from the remainder of the system. 5 One needs only to slip off and pinch closed the various connections to a box to render the box ready for parts replacement or other repair.

If now reference is made to Figures 3, 5 and 6, it will be seen that walk 62 is so positioned and constructed as 10 to facilitate isolation of a pair of jet boxes from the system for easy replacement or repair. To this end a pair of angle members 133 and 134 are supported on the machine frame to run lengthwise thereof near the facing edges of boxes 29 and 44, respectively. Walk 62 is made up of separate planks 135 resting on the members 133 and 134 but not fastened. Thus an operator can move along walk 62 until he reaches a position adjacent a box needing repair and kneel there. In the kneeling position he may lift one or more of the planks 135 thereby exposing the tube group on which work is required.

While the foregoing description makes it clear that the area below the walk 62 is easily accessible there is another problem in gaining access to the boxes 29 and 44 and that is the vapor or gas removal hoods 136 and

25 137. The hoods 136 serve the boxes 29 in groups of six, see Figure 2, and the hoods 137 serve the boxes 44 in the same way, a pair of hoods 136-137 serving paired opposite boxes. Each hood 136 is connected to a high manifold 138 by a connecting conduit 139 and each hood 137 is connected to the same manifold by a conduit 140. The manifold is exhausted by a large fan or gas pump, not shown, acting through a conduit 141 serving the entire manifold 138.

It is apparent that the evolution of gas will of necessity 35 occur where the treating liquids are flowing under conditions of some agitation while exposed to atmosphere. This, in a practical sense, means that the hoods 136 and 137 to be effective should have their mouths above, close to and in registry with the boxes 29 and 44. On 40 the other hand in that position operator access to the boxes 29 and 44 is blocked. This problem is solved in a manner shown in Figures 4 and 12 to 14, inclusive. For purposes of explanation one of the hoods 137 will be described in detail with the understanding that all of 45 the hoods 136 and 137 are made and used in the same way.

In Figure 4 it will be noted that neither of the hoods 136 or 137 extends in a truly vertical direction above the respective boxes 29 and 44. They are held in the 50 position shown, dependent from the conduits 139 and 140, by locks at points 142 and 143 and hinges at 144 and 145. It is now apparent that if the locks 142 and 143 are released the hoods 136 and 137 will swing by gravity about the hinges 144 and 144 to a vertical position shown in broken lines in Figure 4.

Each hood is of rectangular cross section adjacent the 55 hinges 144 or 145 and is provided with a flange, see the flange 146 of Figures 12 to 14. A similar flange is provided on the lower end of the ducts 139 and 140, see the flange 147 of Figures 12 and 14. The hinges 144 lie between these flanges. The locks 142 and 143 are no more than bolts and nuts such as are shown at 148 in Figures 13 and 14.

It can now be seen that when an operator desires access to any of the pairs of boxes 29-44 he not only removes the appropriate plank 135 but also releases the appropriate locks 142-143 so that the hoods will swing away from registry above the boxes. It is found that the vapor evolved during a short repair period from the five 60 exposed boxes which are not served by the hood when it is in the broken line position of Figure 4 is negligible. If the machine were operating under conditions to produce readily dangerous quantities of fumes, it would only be necessary to increase the number of hoods to reduce

the number of boxes served by each hood until a safe condition existed.

Vapor control from above the spinning and hot water baths is best understood by further reference to Figure 4. It will be noted that a closed spaced above the bath tanks 10 and 12 is defined by sliding windows 149, ducts 150 and 151 and a wall 152 through which the drive shafts for the godets pass. The sliding windows expose six spinning positions at a time. Fresh air pumped in through conduit 153 to duct 150 and through small apertures at 154 in its lower wall thereby supplies fresh humidified air to the space above the baths. Through large apertures at 155, duct 151 receives vapors from the baths and these vapors are withdrawn through duct 156.

Acid is supplied to the spin bath in tank 10 through a stand pipe 157 and a similar stand pipe 158 serves the hot water bath in tank 12.

The description has thus far covered the spinning of the yarns and their aftertreatment including the circulation of the various aftertreating liquids. To complete the description from the point of view of yarn handling, it is necessary to describe the manipulations which take place once the yarn issues from the tubes 45. In this discussion reference to Figures 1 and 6 will be helpful.

It will be recalled that troughs 18 and 19 are of V cross section, and slope downwardly from left to right as viewed in Figure 1. A finishing solution is introduced at the upper end of each trough, the slope of the troughs being such that the liquid will flow at a rate a little in excess of the rate of yarn propulsion in the tube groups 14 and 16. The liquid flows from the lower end of trough 18 into the chute 125. A chute 161 performs the same function for the trough 19. Upon leaving the chute 125 the finish is recovered in receptacle 126 while a similar receptacle 162 serves the chute 161 in the same way.

With the finish solution running in the troughs 18 and 19 one is in a position to appreciate the layout of Figure 1. Note that the spinning side of the machine including baths 11 and 13 has a walkway 163 corresponding to walkway 58 and that the groups 16 are served by a walkway 164 like walkway 62, while walk 61 is common to both sides of the machine.

Now suppose the machine of Figure 1 is to be spun-in. One operator spins-in the godets and the tubes 28 from walk 58 and another does the same from walk 163, both beginning at the right end of Figure 1. An operator on walk 62 and another on walk 164 spin-in the tube groups as the yarns issue from the tubes 28. Thus the operators on walks 58, 62, 163 and 164 must work substantially simultaneously as a team. However, since the tubes 45 discharge automatically into the troughs 18 and 19, no particular timing is required of the operator on walk 61 and he can easily serve both sides of the machine.

As the yarns fall into the troughs 18 and 19 they are carried downstream by the current of finishing solution, and because of the graduations in length of the tubes 45 the tendency is for the yarns to separate. After six or more yarns are running in either of the troughs 18 or 19, the operator lifts them out of the trough and slips in a removable comb across the top of the trough. The yarns are then arranged as a warp in this comb. The combs for trough 18 bear reference numeral 165 and those for trough 19 bear reference numeral 166, see Figure 6. As further positions are spun-in the operator repeats the combing operation until finally a warp of seventy-two yarns is running over each of the chutes 125 and 161. These are drawn by drawoff rollers 46 and 167 and delivered to a common warp dryer of the type schematically shown in Figure 2, and described in detail in conjunction with Figure 16. If desired, the first six or twelve yarns spun-in may be combed out and passed through the dryer to the take-up before additional yarns are spun-in. As additional yarns are then spun-in they may be combed out and led through the dryer using the method and de-

vice disclosed in co-pending application Serial No. 262,145, now U.S. Patent No. 2,844,859, dated July 29, 1958.

Referring now to Figure 16, the warp of yarns passing through drawoff rollers 46 and 167 is brought into contact with a first series of rotating drying cylinders 168-179, inclusive. The completely dried yarns leaving the cylinder 179 are guided by freely rotatable rollers 180 and 181 into a bath of finishing solution 182, through driven squeeze rolls 183, 184 and 185 and to a second series of drying cylinders 186-197, inclusive. The second series of drying cylinders 186-197, inclusive, are preferably operated at a speed slightly in excess of that of squeeze rolls 183, 184 and 185 to impart an additional stretch to the once dried yarns. On leaving the final drying cylinder 197, the warp of yarns is passed to any suitable take-up for a continuously running filamentary material. The propulsion of the drying cylinders 168-179, inclusive, is effected by a driving chain 198 which interconnects the cylinders, the drive being imparted to the system through a sprocket 199 coaxial with drying cylinder 172. Sprocket 199 is driven from a chain 200 which in turn is driven from a transmission system generally designated by numeral 201. Drying cylinders 186-197, inclusive, are similarly driven by an interconnecting chain 202 and power is applied from transmission system 201 to this group through a sprocket 203 coaxial with cylinder 193 and suitable chains, as shown.

Inasmuch as various modifications will become apparent to those skilled in this art, it is intended that the scope of this invention be limited only to the extent set forth in the following claim.

What is claimed is:

A continuous viscose spinning machine comprising an elongated spinning bath tank, a plurality of spinnerets supported within said tank at spaced intervals, a first row of jet boxes extending parallel to said spinning bath tank, a second row of jet boxes extending parallel to said spinning bath tank in spaced relationship to said first row, the number of jet boxes in each row corresponding to the number of spinnerets in said spinning bath tank and corresponding jet boxes in each of said rows cooperating to form a plurality of pairs, a plurality of groups of aftertreating tubes, the number of groups corresponding to the number of spinnerets and to the number of pairs of jet boxes, each group consisting of a plurality of elongated tubes extending at right angles to said spinning bath tank with respective ends thereof communicating with and being supported by a cooperating pair of said jet boxes, means to guide and propel yarn from each spinneret to a corresponding group of aftertreating tubes, means for automatically threading said yarn back and forth between each pair of jet boxes and through the group of aftertreating tubes associated therewith, an elongated trough extending parallel to said spinning bath tank but spaced therefrom a distance greater than that between the first and second rows of jet boxes, means to deliver yarn from each group of aftertreating tubes to said trough, and means for withdrawing yarn from said trough in warp form for further processing.
